AUTOMATIC CARBONATING SIPHON BOTTLE

Original Filed Sept. 13, 1937

UNITED STATES PATENT OFFICE

2.173.929

AUTOMATIC CARBONATING SIPHON BOTTLE

**David E. Bowman, Burbank, Calif., assignor to
Siphonator, Inc., Los Angeles, Calif., a corpora-
tion of California**

**Application September 13, 1937, Serial No. 163,693
Renewed February 18, 1939**

7 Claims. (Cl. 226—62)

This invention relates to and has for an object the provision of a simplified and otherwise improved carbonating siphon bottle of the type forming the subject matter of my application for patent, Serial Number 159,613, filed August 17, 1937, wherein a combined carbonating and liquid and gas intaking means mounted within a siphon bottle provides for a thorough carbonating action by saturating the liquid with the gas within the bottle during the intaking of the liquid and gas.

10. See, during the intaking of the liquid and gas.

In the combined carbonator and siphon bottle of my aforesaid application the siphon bottle is equipped with the usual valved dispensing head and a combined carbonating and intaking means,

15 which latter includes a movable liquid discharge tube extending upwardly into the bottle from the bottom thereof. The lower end of the tube is equipped with a liquid intake valve which is opened by pressure of liquid discharging into the

20 tube from a filling fountain, said tube being engaged with the fountain so that the valve of the fountain is thereby opened and the tube is moved upwardly whereby such upward movement will open the gas intake valve in the bottle and thereby allow the gas to enter said bottle. Upon disengaging the tube from the filling fountain the liquid intake valve, constructed as an outwardly closing check, will automatically close and the tube in being spring loaded, will move back to

25 normal position and thereby close the gas intake valve, the pressure within the bottle holding said valve tightly closed.

An object of the present invention is to provide a carbonating bottle of the character described, wherein the liquid intake tube carried by the bottle, is fixed instead of being movable and the intaking of liquid and gas is effected through outwardly opening check valves carried within the bottle, both of which open when the lower end of the tube exposed at the bottom of the bottle is engaged with a filling fountain and liquid and gas under pressure are discharged from said fountain against said valves. In this form the valves will automatically close when the bottle is disengaged from the fountain.

45 A further object of this invention is to provide an automatic carbonating siphon bottle which, together with a filling fountain that may be conveniently located upon a service bar, kitchen shelf or within a refrigerator and connected with sources of supply of liquid and gas under pressure, makes possible an efficacious charging of the bottle with gas and liquid and an automatic carbonating of such components at the 50 time of the discharge thereof into the bottle,

through the simple expediency of placing the bottle against or upon the filling fountain and allowing it to remain until the bottle is fully charged, said bottle being readily removable from the fountain at will, in order to dispense the carbonating liquid as desired. 5

I have shown in the accompanying drawing a preferred form of an automatic carbonating siphon bottle embodying my invention, subject, however, to modification, within the scope of the appended claims, without departing from the spirit of my invention.

Referring to the drawing:

Fig. 1 represents a fragmentary vertical sectional view of the automatic carbonating siphon bottle of this invention as when connected with the filling fountain which is likewise shown in vertical section.

Fig. 2 represents a vertical sectional view of the filling fountain as when closed, and 20

Fig. 3 represents a fragmentary side elevation of the bottle and fountain as when connected.

One embodiment of the automatic carbonating siphon bottle of this invention as shown in the accompanying drawing, comprises the siphon bottle 4 equipped with the usual siphoning or dispensing head 5 and an automatic carbonating and intaking means 6, which latter is adapted to be engaged with a fixed filling fountain 7. As here shown this fountain may be mounted upon a shelf, serving bar or like support 8, or fixed within a refrigerator and connected by pipe lines 9 and 10 with sources of supply of gas and liquid under pressure, not shown. The gas supply line 9 may be equipped with a suitable control valve 11 and a pressure indicator 12, whereas a suitable valve 13 will control the liquid feed to the fountain. The discharge of gas and liquid from the fountain is controlled by valve means 14 in the form of a tubular stem 15 vertically movable in a bore 16 in the body 17 of the fountain. At its upper end this bore is provided with a discharge opening 18 formed on its lower side with a valve seat 19 for an annular valve 20 fixed on the periphery of the tube 15. The valve 20 is normally

the pipe 10 through a passage 26 in a plug 27 to which the line 19 is connected. A valve 28 is normally held closed by a spring 29 to prevent the entrance of liquid from the chamber 25 into the lower end of the tube 15. When this tube is depressed it engages and opens the valve 28 and liquid will flow from the chamber 25 around the valve and into the tube through lateral intake openings 30 in the latter, as particularly shown in Fig. 1. The liquid will pass upwardly through the tube 15 and out through the upper end thereof, which latter extends through the opening 18 so as to leave a space around the tube sufficient for the discharge of gas from the bore 16. This upper end of the tube 15 is disposed in the center of a female coupling 31 secured to the body 17, extending above the shelf 8. This coupling member is provided with interrupted internal screw threads 32 that will as hereinafter described, provide for a quick-detachable connection of the siphon bottle with the fountain.

In accordance with the present invention the carbonating means 6 is constructed so as to be comparatively light and to consist of a minimum number of parts, especially moving parts, the only moving parts necessary being the simple elements of two check valves as will be hereinafter explained. This means 6 comprises a plug-like body member 33 which is screwed into a ring 34 fixed upon an upstanding annular flange 35 formed at the margin of an opening 36 in the bottom 37 of the bottle. The ring 34 is welded or otherwise secured to the flange so as to form a permanent and tight seal. The plug-like body 33 has its lower end formed as a tubular male coupling 38 extended so that it may be engaged in the coupling 31 and connected therewith by means of external screw threads 39 thereon. An annular groove 43 in the plug 33 receives the coupling 38 as indicated in Fig. 1, and may be provided with a cushioning washer or packing ring 41. It will be noted that the lower end of the coupling 39 is disposed slightly above the plane of the lower end of the bottle, the bottom 37 of the bottle being concaved to accommodate this arrangement and to prevent contact of the coupling 38 with the surface upon which the bottle is rested.

When the siphon bottle is coupled with the fountain as shown in Fig. 1, the upper end of the tube 15 of the fountain will engage a compressible ring 42 fixed upon a boss 43 carried by the plug 33. This will depress the tube 15 so as to open the valves 29 and 28, thereby allowing gas and liquid to be discharged by the fountain. The liquid discharging from the tube 15 will enter a passage 44 through the boss 43 and open a check valve 45 mounted in an enlargement 46 of said passage, the pressure of the liquid opening said valve. From this enlarged portion 46 the liquid passes upwardly through a tube 47 fixed to the plug body 33, said tube having an atomized 48 at its upper end which is disposed adjacent the upper end of the bottle. This atomized will cause the liquid to be discharged into the bottle as a fine whirling mist or spray.

The gas from the fountain discharges around the tube 15 into the interior of the coupling 38 and from thence flows through an intake passage 49. A check valve 50 normally closing the passage 49 is opened by the pressure of the gas and permits the gas to discharge through a nozzle 51 mounted in the plug body 33. This nozzle is comparatively small so that the gas enters adjacent the lower end of the body and upon rising therein,

will thoroughly saturate the fine mist or spray of liquid discharging from the atomizer. In this manner the carbonating action takes place at the time that the gas and liquid are introduced, the gas entirely saturating the fine mist of liquid discharging from the atomizer and also by rising through the body of carbonated liquid which collects in the bottle.

It will now be seen that the check valves 45 and 50 control the admission of liquid and gas into the bottle and are opened by the pressure of liquid and gas streams discharging from the fountain. When the bottle is detached from the fountain these valves will automatically close and be held in such position to prevent leakage by the pressure built up within the bottle.

It is now seen that it is only necessary when the bottle is to be refilled and the liquid and gas are thereby carbonated while being introduced into the bottle, to place the bottle upon the fountain and give it a slight turn so as to engage the screw threads 32 and 39 of the coupling members 31 and 38 respectively. This connection will provide at the same time for the openings of the valves 20 and 28 in the fountain, due to the depression of the tube 15 and when these valves 20 and 28 are open, the pressure of the gas and liquid will be applied from the fountain against the valves 50 and 45 respectively, carried by the bottle, whereupon the gas and liquid will be charged into the bottle and the carbonating action hereinbefore described will take place within the bottle during the charging thereof with said gas and liquid. After the bottle has been charged it may be turned slightly, whereby to disengage it from the fountain and then may be removed and used in the ordinary manner to dispense a thoroughly carbonated liquid by manipulation of the siphon head 5 as desired. It is important to note that the bottle is extremely light and consists of comparatively few parts and may be quickly and easily charged as desired, through the provision of this invention, in a most convenient manner. When the fountain is installed, for instance in a refrigerator, the bottle may be connected with a fountain and allowed to remain thus connected until the use of the bottle is required, whereupon but a slight turning movement is necessary to disengage the bottle from the fountain and an entirely charged carbonated liquid may then be dispensed in the ordinary manner.

I claim:

1. A combined siphon bottle and carbonator comprising a bottle having a head for dispensing a carbonated liquid therefrom, and a combined carbonating and liquid and gas intaking means, having elements thereof disposed interiorly and exteriorly of said bottle apart from said head for introducing gas and liquid into said bottle and saturating the liquid with the gas during said introduction of said liquid, said last named means including normally closed check valves carried by said bottle and arranged to be opened by the pressure of the liquid and gas being introduced into the bottle.

2. A self carbonating siphon bottle comprising a bottle having a siphon head for dispensing carbonated liquid therefrom and a combined carbonating and intaking means carried by said bottle for introducing liquid and gas from pressure sources thereof into the bottle apart from said head and operating to saturate said liquid with said gas during said introduction of said liquid, and including valve devices carried by said bottle and separate therefrom, and engage-

- able to effect the opening thereof for establishing a liquid and gas charging connection between said bottle and sources of liquid and gas under pressure, the valve devices carried by said bottle comprising normally closed check valves arranged to open responsive to the pressure of the liquid and gas being charged with said bottle. 5
3. A combined siphon bottle and carbonator comprising a bottle, a siphon head for dispensing carbonated liquid therefrom, and means carried by the bottle apart from said head providing for the introduction of liquid and gas under pressure into said bottle and the saturation of the liquid by the gas during the introduction of the liquid as aforesaid, said last named means being located in the bottom of the bottle and having a portion thereof extended through said bottom, said last named means also including check valves which open under pressure of the fluid being charged into the bottle and are held closed by the fluid pressure in the bottle upon cessation of the charging of the bottle. 10
4. A combined siphon bottle and carbonator comprising a bottle, a siphon head for dispensing carbonated liquid therefrom, means carried by the bottle apart from said head providing for the introduction of liquid and gas under pressure into said bottle and the saturation of the liquid by the gas during the introduction of the liquid as aforesaid, said last named means including separate gas and liquid intake means exposed exteriorly of the bottom of the bottle and including normally closed check valves which open responsive to pressure of the liquid and gas entering through said intake means and also including separate discharge means for discharging the liquid into the bottle adjacent the upper end of the bottle and the gas adjacent the lower end of the bottle. 15
5. A combined siphon bottle and carbonator comprising a bottle, a siphon head for dispensing carbonated liquid therefrom, means carried by the bottle apart from said head providing for the introduction of liquid under pressure into the upper part of the bottle, similar means likewise apart from said head providing for introduction of gas under pressure into the lower part of the bottle, said two intaking means including normally closed valves which open responsive to the pressure of said fluids upon introduction of the latter into the bottle. 20
6. A combined siphon bottle and carbonator comprising a bottle, a siphon head for dispensing carbonated liquid therefrom, an intake fitting extending through the bottom of the bottle, liquid intaking means carried by said fitting and including a tube extending upwardly from said fitting and arranged to discharge liquid in the upper part of the bottle, valve means carried by said fitting for controlling the passage of liquid through said tube and arranged to open under the influence of pressure of liquid charged into said fitting from a source of supply under pressure, and gas intake means carried by said fitting and arranged to discharge gas into the lower part of the bottle, said gas intaking means including a normally closed valve which will open responsive to the pressure of gas charged into the fitting from a source of supply under pressure. 25
7. A combined siphon bottle and carbonator comprising a bottle, a siphon head for dispensing carbonated liquid therefrom, an intake fitting extending through the bottom of the bottle, liquid intaking means carried by said fitting and including a tube extending upwardly from said fitting and arranged to discharge liquid in the upper part of the bottle, valve means carried by said fitting for controlling the passage of liquid through said tube and arranged to open under the influence of pressure of liquid charged into said fitting from a source of supply under pressure, and gas intake means carried by said fitting and arranged to discharge gas into the lower part of the bottle, said gas intaking means including a normally closed valve which will open responsive to the pressure of gas charged into the fitting from a source of supply under pressure, and coupling means provided on the lower end of said fitting for effecting connection of the bottle with sources of supply of liquid and gas. 30
